APPARATUS FOR SHAPING FASTENER ELEMENTS

Edward J. Tuttle, Waterbury, Conn., assignor, by
mesne assignments, to United States Rubber
Company, New York, N. Y., a corporation of
New Jersey

Application July 2, 1937, Serial No. 151,625

10 Claims. (Cl. 29—34)

My invention relates to apparatus for fashioning fastener elements for attachment to fabric edges in slide fastener assemblies.

Fastener elements of this character are small and have to be shaped very accurately. In general, they comprise diverging legs between which the fabric edge is attached and a head having a projection or knob on one side of the head, and a recess on the opposite side for the reception of an adjacent projection. Where such elements are punched out individually from flat sheets of metal, a considerable proportion of the area of the metal strips is scrapped.

In the present invention I provide an element forming machine in which a preformed strip of rod or wire, having a general U shape, is cut to exact length, corresponding to the width of the fastener elements, and completely shaped in a single machine. The machine operates continuously and automatically.

The accompanying drawings illustrate a present preferred embodiment of my invention, in which:

Fig. 1 is a plan view of a machine embodying my invention;

Fig. 2 is a cross sectional view thereof, taken along the section line 2—2 of Fig. 1;

Fig. 3 is a side view of the machine;

Fig. 4 is an elevational view of the strip feeding rollers;

Figs. 5 to 9, inclusive, are detailed sectional views in elevation, showing the different movements of the cooperating punches;

Figs. 10 and 11 are detailed views in elevation of a kick-off mechanism;

Fig. 12 is a diagrammatic view of a knife preparatory to engaging the rod; and

Fig. 13 is a cross sectional view of a finished fastener element.

Referring particularly to Figs. 1, 2, 12, and 13, my machine comprises a pair of feeding rollers 1 for advancing a strip 2 of wire or rod of general U type in cross section, as particularly shown in Fig. 12, into an opening 3 in a die block 4 so that the end is in a position for engagement by a cutting edge 5 of a reciprocating knife 6. The knife 6 removes an end or element blank from the rod 2 of the width of the fastener elements 7. The detached end of the rod 2 is moved by the knife 6 into alignment with an opening in a swedging die 8. A punch 9 removes the detached end from the knife into a through passage 10 of the swedging die 8 so that the knife 6 may be retreated. The passage 10 has an interior configuration conforming to the outer shape of the element 7,

A second punch 11 moves into the passage 10 from the opposite direction and completes the shaping of the element 7. The punch 11 has a projection 12 which cooperates with a socket 13 in the punch 9 to form a projection lug 15 and a socket 16 on each fastener element 7. The punch 11 retreats and the punch 9 follows through to move the element 7 out of the opening 10. A kick-off blade 17 then removes the element and causes it to drop into a chute 18. The punch 9 then retreats and the cycle of operations is repeated.

Referring particularly to Figs. 5 to 9, inclusive, the operation of the knife 6 and the punches 9 and 11 is shown in detail. In Fig. 5 the knife 15 6 has delivered the end of the strip for forming the next element 7 in position opposite the opening 10 in the die 8. In the cutting operation the knife 6 depresses the legs of the element from the cross sectional showing in Fig. 12 to the dotted line position. The positioning of the element blank before the opening 10 is determined in part by an element stop 19.

In Fig. 6 the punch 9 has advanced the element blank into the opening 10 and the knife 25 6 has started to retreat. The punch 11 has started to enter the opening 10. In Fig. 7 the punches 9 and 11 are shown in their pressing or forming positions in the openings 10. At the same time the rod 2 has been advanced over the 30 end of the knife 6 for the next cutting operation, the end of the rod bearing against a structural surface of the bearing block for the die 8.

In Fig. 8 the punch 11 has retreated from the opening 10 and the punch 9 has advanced to position the element 7 beneath the kick-off blade 17.

In Fig. 9 the kick-off blade 17 is shown removing the element 7 with the formed projection 15 from the end of the punch 9 and in position 40 to fall into a chute 18.

Referring particularly to Figs. 10 and 11, the kick-off blade 17 is provided with a beveled edge 20 which engages the edge of the element 7 and causes the latter to turn, as shown, about the 45 socket 13 in the punch 9 thereby obviating any danger of mutilation of the projection 15 on the element 7. A direct blow from the kick-off blade 17 might have a tendency to produce a marring or shearing effect on the projection 15.

In detail, the machine comprises a base plate 21, side plates 22 and 23, and the die block 4 which serves as a cross plate between the side plates 22 and 23. These plates are secured together by any suitable means, as by welding or 55

by screws, not shown. A shaft 25 is mounted in the side plates 22 and 23 and extends outwardly therebeyond. A pulley 26 is connected to any usual prime mover by a belt 27.

5 The feeding rollers 1, as illustrated in Fig. 4, are given complementary shapes to fit into the channel of the rod 2 and are mounted in a frame 28 secured to the rear of the frame by suitable means, not shown. The rollers are carried in 10 upper and lower sets of bearings 29 and 30, respectively, the relative position of which may be slightly adjusted by a set screw 31 extending from the top of the frame 28 for engaging a cross bar 32 resting on the bearings 29. The lower roller 15 is mounted on a shaft 33, working against a brake 34, to the outer end of which is attached a gear 35. The gear 35 meshes with a gear 36 on the shaft 37 of the upper roller. The shaft 33 extends through a bearing block 38 projecting from the 20 end of the side plate 22. A ball bearing clutch 39, illustrated in Fig. 3, is attached to the end of the shaft 33 and is connected by a rod 40 to an eccentric 41 on the shaft 25. Accordingly, with each revolution of the shaft 25 the clutch 39 is 25 caused to actuate the shaft 33 to advance the rod 2 by the desired amount. Because of the relatively small movement required, it is preferred to use the type of clutch illustrated, rather than a conventional pawl and ratchet as the latter 30 type of clutch occasionally has slippage by reason of failure of the teeth to properly register or mesh.

The knife 6 is adjustably mounted in a block 42 sliding in a vertical way 43. A clamping plate 44 is secured by screws 45 to hold the knife 6 35 against the block 42. When the position of the knife 6 is to be changed, the screws 45 are loosened. Further adjustment of the knife 6 is secured by having its lower end engage a sloping surface 46 in an adjusting bar 47 secured by a 40 screw 48. By adjusting the screw 48 the bar 47 may be moved in or out to give the final adjustment of the position of the knife 6.

The block 42 is actuated by a cam 49 working against compression springs 50 seated in the block 45 and the block 42. Accordingly with each revolution of the shaft 25 the knife 6 is raised and lowered once in accordance with the shape of the cam 49.

The punch 9 is mounted in a slide block 51 sliding in a way formed by plates 52 and 53 with overhanging plates 54 and 55, respectively, secured by bolts 56 to the top of the die block 4. The punch 9 is secured by a clamp block 57 and screws 58 to the slide block 51. This position may be adjusted by a wedge 59 having a tapered end 60 and controlled by an adjusting screw 61. The element stop 19 is secured by screws 62 to the plates 52 and 53, as is the die 8.

Reciprocation of the slide block 51 is controlled 60 by a cam 63 mounted on a shaft 65 and engaging rollers 66 on the ends of the slide block 51. The shaft 65 is secured to the tops of the plates 52 and 53 by bearings 67 and 68, respectively. The shaft 65 is actuated by a gear 69 meshing with a gear 70 which, in turn, meshes with a gear 71 mounted 65 on the shaft 25. The various movements of the punch 9, as heretofore described, are controlled by the shape of the cams 63. The cams 63 operate against compression springs 72 and 73 bearing on arms 75 and 76 seated in recesses 77 and 78 in the plates 53 and 52, respectively.

The punch 11 is disposed in a slide block 79 mounted between the plates 53 and 52. As the slide blocks 51 and 79 are of similar construction and mounting, a detailed description of the con-

struction and mounting of the slide block 79 is omitted. The slide block 79 is actuated by a cam 80 mounted on shaft 81 and secured by bearings 82 and 83 to the plates 52 and 53, respectively. The shaft 81 is driven by a gear 85 meshing with a gear 86 which, in turn, meshes with the gear 71 on the shaft 25.

5 The kick-off blade 17 is pivotally mounted on the end of a lever 87 which is pivotally mounted on a bearing 88 attached to the plate 52. The other end of the lever 87 is attached to a tension spring 89 which is secured to a bar 90 extending from the side plate 22. On the end of the shaft 81 there is a cam 91 which bears against the under side of the lever 87 actuating it against the tension of the spring 89. Accordingly, the kick-off blade 17 makes one reciprocation with each revolution of the shaft 81.

10 Accordingly, I have provided a machine for feeding pre-shaped strips of rod or wire; cutting off the ends thereof to form blanks; positioning the several blanks in front of the forming die; transferring the blanks into the die; completing the shaping operation in the die; and discharging the shaped fastener elements. The machine is 15 continuous and automatic in its operation.

15 While I have shown and described a certain present preferred embodiment of the invention, it is to be understood that the invention may otherwise be embodied within the spirit of the invention and the scope of the appended claims.

20 Having thus described my invention what I claim and desire to protect by Letters Patent is:

25 1. A machine for making separable fastener elements comprising a cutting die, means for feeding a predetermined length of preformed wire through said die, means for cutting off the length of wire to form an element blank, a shaping die having a through shaping passage therein, means for conveying said blank into one end of said 30 passage, means for finally shaping said blank into an element within said passage, and means for discharging said element from the opposite end of said passage.

35 2. A machine for making separable fastener elements comprising a cutting die, means for feeding a predetermined length of preformed wire through said die, a shaping die having a through shaping passage therein, means for cutting off a length of wire to form an element blank and for 40 conveying said blank to one end of said passage, a punch for conveying said blank into said passage, a second punch movable into said passage from the opposite end of said passage, and means for operating said punches so that said blank is 45 pressed between the ends of said punches in said passage and thereby finally shaped into a fastener element, the operating means for the second punch having provision for withdrawing the punch from said shaping position, and the operating means for the first punch having provision for continuing the movement of the punch in the direction of the withdrawing movement of the second punch to discharge said element from said 50 passage.

55 3. A machine for making separable fastener elements comprising a cutting die, means for feeding a predetermined length of wire through said die, a shaping die having a through shaping passage therein, means for cutting off a length of wire to form an element blank, and for conveying said blank to one end of said passage, a punch for conveying said blank into said passage, a second punch movable into said passage from the opposite end of said passage, means for operating 60 said second punch to discharge said element from said passage, and means for continuing the movement of the punch in the direction of the withdrawing movement of the second punch to discharge said element from said 65 passage.

70 4. A machine for making separable fastener elements comprising a cutting die, means for feeding a predetermined length of wire through said die, a shaping die having a through shaping passage therein, means for cutting off a length of wire to form an element blank, and for conveying said blank to one end of said passage, a punch for conveying said blank into said passage, a second punch movable into said passage from the opposite end of said passage, means for operating 75 said second punch to discharge said element from said passage, and means for continuing the movement of the punch in the direction of the withdrawing movement of the second punch to discharge said element from said 75 passage.

ing said punches so that said blank is pressed between the ends of said punches in said passage and thereby finally shaped into a fastener element, the operating means for the second punch 5 having provision for withdrawing the punch from said shaping position, the operating means for the first punch having provision for continuing the movement of the punch in the direction of the withdrawing movement of the second punch 10 to discharge said element from said passage, and means for discharging said element from between the ends of said punches.

4. A machine for making separable fastener elements comprising a cutting die, means for feeding a predetermined length of wire through said die, a knife carried by a slide for cutting off the length of wire to form an element blank, a shaping die having a through passage therein, a cam for operating said slide and knife to form 15 said blank and convey it to one end of said passage, a punch and a punch supporting slide at one end of said passage for conveying said blank into said passage, a second punch movable into said passage from the opposite end thereof, a 20 supporting slide for the second punch, cams for operating said slides and punches so that said blank is pressed between the ends of said punches in said passage and thereby finally shaped into a fastener element, resilient means 25 cooperating with said slides and cams for withdrawing said slides, the second punch being withdrawn from the shaping position while the movement of the first punch is continued in the direction of the withdrawal movement of the 30 second punch to discharge said element from said passage, said cams being positioned on substantially parallel shafts extending transversely to the feeding movement of said wire, and means for driving said shafts in timed relation to one another.

40 5. A machine for making separable fastener elements comprising a cutting die, means for feeding wire through said die, a stop for contacting the end of the wire to control the length of wire fed through said die, means for cutting off the length of wire fed through said die to form an element blank, a shaping die having a through passage therein, means for conveying said blank into one end of said passage, means 45 for shaping said blank into an element within said passage, and means for discharging said element from the opposite end of said passage.

55 6. A machine for making separable fastener elements each having a head and laterally extending jaw portions, said machine comprising a cutting die having an orifice provided with a head and jaw portions conforming substantially to the shape of the heads and jaws of said elements, means for feeding a predetermined length of wire having element head and jaw forming 60 portions through said orifice, a shaping die having a through shaping passage therein, a knife having a cutting edge conforming to the outer contour of the element head and jaw forming portions of the wire, means for operating said 65 knife cutting edge against said length of wire from the element head to the element jaw forming

ing portions to cut an element blank therefrom and carry it opposite one end of said shaping passage, means for conveying said blank into said passage, means for shaping said blank into an element within said passage, and means for discharging said element from the opposite end of said shaping passage.

7. A machine for making separable fastener elements comprising a cutting die, means for feeding a predetermined length of preformed 10 wire through said die, a shaping die having a through shaping passage therein, means for cutting off a length of wire to form an element blank and for conveying said blank to one end of said passage, a punch for conveying said 15 blank into said passage, a second punch movable into said passage from the opposite end of said passage, said punches having provision for forming a socket on one face of the element and a projection on the opposite face, and means for 20 operating said punches so that said blank is pressed between the ends of said punches in said passage and thereby finally shaped into a fastener element, the operating means for the second punch having provision for withdrawing 25 the punch from said shaping position, and the operating means for the first punch having provision for continuing the movement of the punch in the direction of the withdrawing movement of the second punch to discharge said element from 30 said passage.

8. In a fastener forming machine, a shaping die having a through passage, a punch having an element projection shaping recess at one end for moving an element through said passage, a 35 cooperating punch for forming a fastener element in the passage, and means disposed at the discharge end and laterally of the passage and movable into the projection of the passage for removing the element from the punch recess.

40 9. In a fastener forming machine, a shaping die having a through passage, a punch having an element projection shaping recess at one end for moving an element through said passage, a 45 cooperating punch for forming a fastener element in the passage, a tapered blade disposed at the discharge end and laterally of the passage, and means for moving said blade transversely of said passage into contact with the element, and thereby turning the element projection in said recess and removing the element from the end of said punch containing said recess.

50 10. In a fastener forming machine, a shaping die having a through passage, a punch having an element projection shaping recess at one end for moving an element through said passage, a 55 cooperating punch for forming a fastener element in the passage, a tapered blade disposed at the discharge end and laterally of the passage, and means for actuating the punches and blade in synchronism, including means for actuating said blade transversely of said passage into contact with the element, and thereby turning the element projection in said recess and removing the element from the end of said punch containing said recess.

EDWARD J. TUTTLE.
